UNITED STATES PATENT OFFICE.

EDWIN F. LEILICH, OF SAN FRANCISCO, CALIFORNIA.

BED-MOTION FOR CYLINDER PRINTING-PRESSES.

No. 852,124.

Specification of Letters Patent.

Patented April 30, 1907.

Application filed October 23, 1902. Renewed June 4, 1906. Serial No. 320,055.

To all whom it may concern:

Be it known that I, EDWIN F. LEILICH, a citizen of the United States, residing in the city and county of San Francisco and State of California, have invented certain new and useful Improvements in Bed-Motions for Cylinder Printing-Presses, of which the following is a specification.

My invention relates to printing presses having a flat bed and type form, and my objects are first; to provide means of great strength, rigidity and simplicity, for driving the bed to and fro, having a minimum amount of gearing between the cylinder and bed during the printing stroke, with an isochronous movement relative to the cylinder while printing, and for reversing the direction of movement of the bed with substantially a crank movement, and by which the bed shall be driven during its printing stroke by one mechanism, during its return or non printing stroke by another mechanism and reversed in its direction of movement by a mechanism different from either of those used to drive it to and fro. Second; to cause the transfer of the control of the bed, from the mechanisms to drive the bed to and fro, to the mechanism for reversing its direction of motion, and vice versa, to take place smoothly and at the same speed. Third; to increase the speed of operation. Fourth; to secure and maintain a better register. Fifth; to provide means for easily and efficiently lubricating interior parts.

The advantages of the construction, hereinafter described, over all others known to me, are many and great.

In order to secure a higher rate of speed the kinetic energy of the reciprocating parts to be arrested at each end of the to and fro movement of the bed, should be as small as possible, the weight of metal in the bed properly distributed and as little as is consistent with the heaviest impression that may be placed upon it. To get a perfect register requires a mechanism to drive the bed to and fro while printing with an isochronous motion relative to the printing surface of the cylinder; this provided, the great pressure of the cylinder on the bearers, necessary in many cases to prevent slipping or lagging between them may be relieved, and a rack on the bed engaging with a gear on the cylinder to force and compel a uniform relative motion of the cylinder and bed rendered unnecessary.

In the presses in common use with which I am familiar, the bed is driven in both directions by one and the same means, thus causing extra wear, loss of motion and consequent loss of register. To obtain the desired higher speed I firmly secure to a bed properly designed and of sufficient weight to stand the heaviest strain of the impression, a single rack with teeth projecting downwardly, and but little below the under surface of the bed and engaged by the means hereinafter described, to drive the bed to and fro, and two hangers with studs and rollers thereon, acting in conjunction with means to reverse the direction of motion of the bed, both the rack and hangers being very strong and rigid, and adding but little to the weight of the bed, in comparison with the heavy double racks with oppositely facing teeth, gates and other devices, carried upon the beds of presses in common use. I secure a more perfect register by the means hereinafter described, by which the cylinder and bed are driven with an isochronous movement at the printing line, with a less amount of gearing between them during the printing stroke than during the return stroke. I also drive the bed throughout the printing stroke by separate and distinct means, which do no work on the return or non printing stroke, and which engage with the bed rack in a separate and distinct path of travel. I return the bed on its non printing stroke by another separate and distinct means, likewise engaging with the rack in a separate and distinct path of travel, and I accomplish the reversal of the direction of the movement of the bed by further means different and distinct from either. I secure rigidity and strength, by supporting the driving gears and reversing cam respectively around and on the same shaft between two bearings comparatively near together and to maintain a better register during long use, without renewing worn parts, I provide simple adjustable means for taking up lost motion in the teeth of the gearing between the cylinder and bed. By this particular construction and combination of parts, I am able to use a comparatively low frame and also, as hereinafter described, to easily lubricate parts that would otherwise be difficult so to do.

My invention therefore resides in the novel construction, combination and arrangement of parts for the aforesaid ends as hereinafter

fully specified, illustrated in the drawings and pointed out in the claims.

In the drawings Figure 1 is a side elevation illustrating certain of the parts in position and partly broken away, to show more clearly interior parts and their connections, the frame work of the press being omitted. Fig. 2 is an end elevation with the bed and frame in cross section on a line $v-v$, in Fig. 3, looking toward the front of the press, or in the direction of the arrow. Fig. 3 is a plan view with the bed removed, the rack partially broken and with the reversing hangers attached to the bed and supports for the latter in cross section, the cylinder being omitted. Fig. 4 is an end elevation in cross section of the bed rack, the printing stroke gear, the return stroke gear, the sleeve and main shaft extending through it, and other connected parts. Fig. 5 shows a part of the eccentric oscillating mechanism separated from its connection with the other parts illustrated in Fig. 4. Fig. 6 is a side elevation of Fig. 4 with the main shaft and parts supported by it cut off on line W and viewed toward the left hand, the printing stroke gear is shown as engaged with the bed rack, and the return stroke gear as out of engagement therewith, the latter gear being broken away to show clearly the printing stroke gear behind it, the gear to the right is a part of the means for rotating the return stroke gear in the opposite direction to the printing stroke gear. Figs. 7, 8 are side and end elevations of the eccentrics and sleeve, in the position in which the eccentrics are placed when the printing stroke gear is engaged with, and the return stroke gear is disengaged from, the bed rack. Figs. 9, 10 are similar to Figs. 7, 8 but show the eccentrics in their opposite positions on the sleeve in which the printing stroke gear is disengaged from, and the return stroke gear is engaged with, the bed rack. The eccentrics and sleeve are illustrated in broken cross section, to show the oil-chambers and conduits for conveying oil from an outside supply to the several surfaces in frictional contact. Figs. 11, 12 are side and end elevations of the sleeve and part of the shaft, with the former in broken cross sections to show the oil-chamber. Figs. 13 to 18 inclusive, are elevations viewed from the feeder side of the press, of the reversing cam with the studs and rollers secured to the hangers attached to the bed in the cam path in three different positions at each end of the to and fro movements of the bed, and showing sections of the bed rack, the driving gear in various corresponding positions, and with the connection between the printing stroke gear and reversing cam likewise in different positions. Figs. 19, 20 are front and side elevations of a gear wheel constructed with two series of teeth of the same diameter and

pitch, secured to each other and provided with means for adjusting one of the series relatively to the other along the pitch lines. Fig. 21 is a cross section of Fig. 19 on line $x-x$. Fig. 22 is a diagrammatic view of the reversing cam, showing an approximative cam path, with the cam roll in its entering position on the first ordinate, and illustrating the movement of the roll in the cam path along the ordinal lines during each 15° of rotation, of the cam. 75

In the illustration and description of this invention, many of the usual and necessary parts in printing presses of like character have been omitted, as not essential to a clear understanding of it. In the drawings, a frame 1 supports one of the ends of each of the shafts shown in Figs. 2, 3 their opposite ends being supported in one or more bearings in uprights $1^a, 1^b, 7^c$ rising from the girth 2 secured between the side frames of the press. 80 Some of these uprights serve to support the bed 3 on rollers as shown. A bed 3 is moved to and fro as hereinafter described, and is provided with a rack 3^a with teeth projecting downwardly, firmly attached to the under side of the bed and of sufficient width to enable the gear wheels hereinafter described, to engage with it in separate lines of travel. A cylinder 4 is shown as supported at one end in one side of the frame 1 the other side being 95 cut away.

Power is communicated to drive the mechanism by a belt pulley secured to a short shaft 5 journaled at one end in the frame 1, and at the other in a bracket, not shown, and has firmly secured to it a broad pinion 5^a , engaging with a gear 6, fixed upon the main shaft 6^a and also with a gear 7, secured to one end of a shaft 7^a . The main shaft 6^a , as seen in Figs. 2, 3, 4 supports between the uprights $1^a, 1^b$, a printing stroke gear 8, rotatably mounted on an eccentric 9 oscillated upon a sleeve 12, supported around the main shaft 6^a , as herein after described. In Fig. 4 the printing stroke gear 8 is illustrated as in gear with the bed rack 3^a . A return stroke gear 10 is rotatably mounted by the side of the printing stroke gear 8 upon an eccentric 9^b , connected to the eccentric 9 in about an opposite position and likewise surrounding the sleeve 12. A reversing cam 11, is rigidly secured to the main shaft 6^a , and transmits motion to the printing stroke gear 8 through the stud 8^a , secured to the side of the printing stroke gear 8 and extending into a slot 11^a , formed in the reversing cam 11, the stud 8^a carries on its free end a slide block 8^b , by which a better wearing surface is obtained between it and the walls of the slot 11^a . The return stroke gear 10 is rotated in an opposite direction to the printing stroke gear 8 by the gear 7^b , fixed upon one end of the shaft 7^a . 115 The gears 8 and 10 are alternately moved, 120

The gears 8 and 10 are alternately moved, 125

- as hereinafter described, in and out of the path of the rack 3^a, in about a vertical plane relative to the movement of the rack 3^a. In order that the bed should be driven to and fro at a uniform rate of speed, more particularly throughout the printing stroke, I have invented the means hereinafter described, whereby the centers of the gears 8 and 10 respectively, when in engagement with the rack 3^a, always coincide with the center of the main shaft 6^a around which they independently are supported, and drive the rack 3^a, and bed 3, to and fro isochronously relatively to the printing surface of the cylinder.
- When the printing stroke gear 8 is disengaged from the rack 3^a, and in its lowest position, it is driven by its connection 8^a, 8^b, with 11^a, with a variable motion, caused by the relative change of centers of the printing stroke gear 8, and the reversing cam 11, but as the gear 8 is at this time out of engagement with the rack 3^a, no undesirable effect follows. The return stroke gear 10 rotates at a uniform rate of motion in either of its positions. Immediately surrounding the main shaft 6^a and placed eccentrically thereto, is a sleeve 12, one end of which enters a bearing in the upright 1^a, where it is held in a fixed position by suitable means, as a screw shown in Figs. 3, 4 with its line of centers placed in about a vertical position relative to the movement of the rack 3^a. Referring to Fig. 4 it might seem that the sleeve 12 supports the main shaft 6^a, which is not the fact, the weight of the latter being sustained by the bearings in the frame 1 and upright 1^b. The eccentric sleeve 12 extends between the inside face of the reversing cam 11 and the upright 1^a, to form a bearing for the eccentrics 9, 9^b which are oscillated upon it, these eccentrics are preferably made in one piece and placed oppositely relatively to each other, as illustrated in Figs. 7 to 10 inclusive. Figs. 7, 8 show the eccentric 9, on which the printing stroke gear 8 is supported, in its upper position, with the latter engaged with the rack 3^a, and the eccentric 9^b on which the return stroke gear is supported, disengaged from the rack 3^a, and in its lower position.
- Figs. 9, 10 illustrate the eccentrics 9, 9^b in opposite positions to those in Figs. 7, 8. In order to move the gears 8 and 10 in and out of the path of the rack 3^a, the eccentrics 9, 9^b must have a throw or vertical movement equal to the full depth of the teeth of the gears 8 and 10, plus a sufficient amount for the safe clearance of their teeth from the rack teeth, when said gears are alternately in their lowest positions.
- Referring to Figs. 6, 8, 10 and 12 two dotted lines k, 1 will be seen extending from the vertical center of the main shaft 6^a below its horizontal center line, the distance between the horizontal center line and line 1 representing the throw of the eccentrics 9, 9^b and the intersection of the vertical center line with the line k the center around which the said eccentrics are oscillated.
- In order that the printing stroke gear 8 should be driven by the cam 11 with a uniform motion when in its upper position and engaged with the rack 3^a, it is necessary that its center should then coincide with the center of the main shaft 6^a and the cam 11 fixed upon it and by which the gear 8 is driven.
- In order to use the printing stroke gear 8 and return stroke gear 10 in combination with a single rack with downwardly projecting teeth secured to the under side of the bed, it is necessary that each of said gear wheels 8^a should be alternately moved in and out of the path of the rack at certain times, in order to do this the sleeve 12 is essential, as by placing it eccentrically relative to the shaft 6^a in a fixed position I am able to locate the center of oscillation of the eccentrics 9, 9^b below the center of the shaft 6^a, and upon the intersection of the vertical center line and horizontal line k, and to cause the concentric centers of the eccentrics to describe a curved path in their movement around the center of oscillation, from their upper to their lower positions and vice versa, as illustrated in Figs. 8, 10 and 12. The effect of this upon the printing stroke gear 8 is, that in its upper position, in which it is engaged with the rack 3^a, its center is concentric with that of the shaft 6^a and it is rotated with an isochronous movement, and when in its lower position and disengaged from the rack 3^a, and consequently doing no work, it is rotated with a variable motion. The surfaces of the eccentrics 9, 9^b are therefore, when in their upper positions, concentric to, and struck from, the intersection of the vertical and horizontal center lines through the center of the main shaft 6^a, and when in their lower positions, are concentric to, and struck from, the intersection of the line 1 with the vertical center line of the shaft 6^a and fitted to be oscillated upon the sleeve 12. A washer 13 held by a screw to the side of the eccentric 9^b holds the return stroke gear 10 in position. I prefer that the gears 8 and 10 and cam 11 shall rotate three times during each reciprocation of the bed, but other proportions may be used if desired.
- The surface of the sleeve 12 is concentric to, and is struck from, the intersection of the line k with the vertical center line of the main shaft 6^a. In order that the eccentrics 9, 9^b may be easily and efficiently lubricated where they are in frictional contact with the gears 8 and 10 and the sleeve 12, the latter being also in frictional contact with the main shaft 6^a, I make in the thicker part of the sleeve 12 a longitudinal cavity or oil-chamber 12^a open at the end by which said sleeve is held in a fixed position as seen in Figs. 4 and 8 to 12 inclusive into which may be 130

Fig. 22 is a diagrammatic view of the reversing cam 11, corresponding in position to Fig. 16 and showing an approximative cam path 11^b with the entering cam roll 16^a in dotted position, the direction of rotation being shown by the arrow; the ordinal lines are 15° apart and the distances between the downwardly projecting lines z^1 from 0° to 90° and from 90° to 180° indicates the distance traveled by the cam roll 16^a in the path 11^b along the ordinal lines in moving to and from the center of the cam in retarding and accelerating the movement of the bed.

It is one of the objects of this invention that the transfer of the control of the movement of the bed, from the rack 3^a to the reversing cam 11, and vice versa, shall take place quietly and without a jerk, therefore in constructing such a cam for practical service, the platting of the path 11^b must be such that the roll will be driven along the longitudinal line $y-y$ toward the center the distance between the vertical lines z^1 from 0° to 15°, while the cam is being rotated 15°, or through the space between the first and second ordinal lines, or, while the cam roll has moved from b to c , the cam has rotated from d to b , both the cam and roll moving at the same rate of speed along the curve f along the path 11^b.

When the cam roll 16^a is in the position shown in Figs. 22 and 16 the bed 3 is controlled by both the return stroke gear 10 and the cam 11, the necessity is therefore evident for the correspondence in their rate of motion; when the cam 11 has rotated 15° after the cam roll 16^a has entered the cam path 11^b, the rack 3^a has moved out of engagement with the return stroke gear 10, which is then moved to its lower position, and the printing stroke gear 8 is simultaneously raised to its highest position, during which time the cam roll 16^a has continued its movement along the ordinal lines to the center, the related parts then corresponding in position to Fig. 17, when the direction of its motion is reversed, moving along the ordinal lines from the center to 165° from its entering point, the rack 3^a, then starting on the printing stroke engages with the printing stroke gear 8, the rack 3^a being under the control of the latter and the reversing cam 11 during its remaining 15° of rotation.

The cam development is alike on its entering and discharging sides and the cam roll 16^a consequently moves in the path 11^b along the curve g at the same rate of speed as on the entering side, and thus the transfer or change of control of the rack 3^a from the gears 8 and 10 alternately to and from the reversing cam 11 is effected smoothly and without a jarring motion.

A gear wheel 18 having cut in its periphery teeth of a desired pitch, is provided with a flange 18^a projecting from one of its sides

and turned concentrically to receive an annular ring 18^b provided with a series of teeth of the same diameter and pitch as those cut in the wheel 18, the screws shown as extending through the slots in the ears or projections 18^c, are threaded in the wheel 18 and secure the gear ring 18^b to the latter and also permit the two series of teeth to be adjusted relatively to each other along their pitch lines, thereby compensating for wear or lost motion between the teeth of any third series of like pitch with which they may be engaged.

While I have illustrated and described my invention in a preferred form of construction I do not desire to be understood as limiting myself thereto, as it is evident that many changes and modifications may be made within the scope and without departing from the spirit of the invention. The gist of my invention lies therefore, not only in the novel construction, combination and arrangement of parts shown and described, and their equivalents, but broadly and more particularly in driving the bed of a printing press to and fro by two separate and distinct sets of mechanisms, and reversing its direction of motion by a third set separate and distinct from those for driving it to and fro; in supporting the rotative parts of the said three mechanisms around and upon one shaft between two bearings; in means for moving the bed driving gear wheels in and out of the path of the bed rack; in means for oiling the parts located upon said shaft between the bearings thereof, and means for taking up wear or lost motion in the gearing between the cylinder and bed of a printing press.

What I claim as new, and for which I desire to secure Letters Patent, is:

1. In a printing press comprising among its elements a bed and rack; a rotating shaft, means for moving the bed in one direction, a second means for moving the bed in the opposite direction, a body rigidly secured to said shaft and confined to movement in a single plane, and an operative connection between said body and second means.

2. In a printing press comprising among its elements a bed and rack; a rotating shaft, two gear wheels supported around said shaft, means for rotating one of them in a direction opposite to that of said shaft, a body rigidly secured upon said shaft, and an operative connection between said body and the other of said gear wheels.

3. In a printing press comprising among its elements a bed and rack; a rotating shaft supported in two bearings, two gear wheels surrounding said shaft, means for rotating one of them in an opposite direction to that of said shaft, a body rigidly secured to said shaft, and an operative connection between said body and the other of said gear wheels;

- to communicate motion from the former to the latter, said body and gear wheels being supported upon and around said shaft between the two bearings thereof.
5. 4. In a printing press comprising among its elements a bed and rack; a shaft supported in two bearings, two gear wheels surrounding said shaft between the bearings, means for rotating one of them in one direction, means for giving said gear wheels vertical reciprocations, a rotating body, and an operative connection between said body and the other of said gear wheels; to communicate motion from the former to the latter.
15. 5. In a printing press comprising among its elements a bed and rack; a rotating shaft, two gear wheels surrounding said shaft, means for rotating one of them in a direction opposite to that of said shaft, means for giving said gear wheels vertical reciprocations, a body rigidly secured to said shaft, and an operative connection between said body and the other of said gear wheels; to communicate motion from the former to the latter.
25. 6. In a printing press comprising among its elements a bed and rack; a sleeve, a shaft, means for rotating it, the shaft being extended through the sleeve eccentrically thereto, one or more eccentrics supported on the sleeve, and one or more gear wheels supported on said one or more eccentrics.
35. 7. In a printing press comprising among its elements a bed and rack with downwardly projecting teeth; a shaft supported in two bearings, two gear wheels supported around said shaft between the bearings, means for rotating one of them in one direction, a body supported upon said shaft, an operative connection between said body and the other of said gear wheels, and means for alternately moving each of said gear wheels in and out of the path of said rack.
45. 8. In a printing press comprising among its elements a bed and rack; a shaft, two gear wheels surrounding said shaft, means for rotating them in opposite directions, a sleeve placed eccentrically around said shaft and held in a fixed position by an attachment to the frame, two eccentrics supported upon said sleeve and supporting said gear wheels, and means for alternately reversing the position of said eccentrics and gear wheels.
55. 9. In a printing press comprising among its elements a bed and rack; a shaft, two gear wheels surrounding said shaft, means for rotating one of them in one direction, a body supported upon said shaft, means for rotating said body in an opposite direction to the last named gear wheel, an operative connection between said body and the other of said gear wheels, to communicate the motion of the former to the latter, a sleeve placed eccentrically around said shaft and held in a fixed position by an attachment to the frame, two eccentrics supported upon said sleeve and supporting said gear wheels, and means for alternately reversing the position of said eccentrics and gear wheels.
65. 10. In a printing press comprising among its elements a bed and rack; a rotating shaft, two gear wheels surrounding said shaft, means for rotating one of them in a direction opposite to that of said shaft, a body rigidly secured to the rotating shaft, an operative connection between said body and the other of said gear wheels, to communicate the motion of the former to the latter, a sleeve placed eccentrically around said shaft and held in a fixed position by an attachment to the frame, two eccentrics supported upon said sleeve and supporting said gear wheels, and means for alternately reversing the position of said eccentrics and gear wheels.
11. In a printing press comprising among its elements a bed and rack; means for moving the bed in one direction, a second means for moving the bed in the opposite direction, and a third means for reversing the direction of the movement of the bed, said third means including two hangers rigidly attached to the bed and bearing each a stud and roller, to alternately engage with and disengage from the rotating element of said third means, each of said means being confined to movement in a single plane.
12. In a printing press comprising among its elements a bed and rack; means for moving the bed in one direction, a second means for moving the bed in the opposite direction, a shaft supported in two bearings, two hangers suitably attached to the bed and bearing each a stud and roller, a cam supported upon said shaft between the two bearings, and means for rotating said cam to alternately engage with and disengage from said studs and rollers, to reverse the direction of the movement of the bed, each of said means being confined to movement in a single plane.
13. In a printing press comprising among its elements a bed and rack; a shaft supported in two bearings, two gear wheels surrounding said shaft between the bearings, means for rotating one of them in one direction, two hangers suitably attached to the bed and bearing each a stud and roller, a cam supported upon said shaft between the bearings, means for rotating said cam in an opposite direction to that of the gear wheel last named, to alternately engage with and disengage from the said studs and rollers, to reverse the direction of the movement of the bed, and an operative connection between said cam and the other of said gear wheels.
14. In a printing press comprising among its elements a bed and rack; a rotating shaft supported in two bearings, two gear wheels surrounding said shaft, means for rotating one of them in a direction opposite to that of said shaft, two hangers suitably attached to the bed and bearing each a stud and roller, a

cam rigidly fixed upon the rotating shaft between the two bearings, to alternately engage with and disengage from the said studs and rollers, to reverse the direction of the 5 movement of the bed, an operative connection between the cam and the other of said gear wheels, and means for alternately moving each of said gear wheels in and out of the path of the rack; to drive the latter and bed 10 attached thereto to and fro.

15. In a printing press comprising among its elements a bed and rack; a rotating shaft, a gear wheel supported around said shaft, means for moving said gear wheel in and out 15 of the path of said rack, a body rigidly fixed upon said shaft, a stud secured to said gear wheel provided with a block, and a slot formed in said body with which said stud and block engages; whereby the motion of 20 the body is communicated to the gear wheel.

25. In a printing press, comprising among its elements a bed and rack; a rotating body, a gear wheel, an operative connection between the former and the latter, and means 30 for changing the position of the center of the gear wheel relatively to that of the rotating body, to move the gear wheel in and out of the path of the rack; whereby the gear wheel when in a position in which its center coincides with the center of the rotating body is driven with an isochronous movement and when in other positions with a variable movement.

35. In a printing press comprising among its elements a bed and rack; a rotating shaft, a gear wheel supported around said shaft, a body rigidly secured upon said shaft, an operative connection between said gear wheel and body, and means for giving vertical reciprocations to said gear wheel.

40. In a printing press comprising among its elements a bed and rack; a rotating shaft, a gear wheel surrounding said shaft, means for moving said gear wheel in and out of the path of said rack, a cam rigidly secured to 45 said shaft, and an operative connection between said cam and gear wheel.

45. In a printing press comprising among its elements a bed and a single rack; a rotating shaft, a gear wheel surrounding said shaft, an operative connection between said shaft and gear wheel, and means for giving vertical reciprocations to said gear wheel.

50. In a printing press comprising among its elements a bed and rack; a shaft, two gear wheels surrounding said shaft, means for giving alternate reciprocations to each of said gear wheels, comprising a sleeve placed eccentrically around said shaft and held in a fixed 55 position by an attachment to the frame, two eccentrics supported upon said sleeve and supporting said gear wheels, and mechanism for alternately reversing the position of said eccentrics and gear wheels; to move the latter 60 in and out of the path of the rack.

21. In a printing press comprising among its elements a bed and rack; a shaft, two gear wheels surrounding said shaft, and means for giving alternate reciprocations to each of said gear wheels, comprising a sleeve placed eccentrically around said shaft and held in a fixed 70 position by an attachment to the frame, two eccentrics supported upon said sleeve and supporting said gear wheels, a gear 14 secured to a collar extended from one of the eccentrics, and a geared sector engaging with the gear 14 fixed upon a shaft having a bearing in the frame, said shaft having secured to its opposite end an arm provided with a stud and roller engaging with a rotating cam. 75

22. In a printing press comprising among its elements a bed and rack; a shaft, a sleeve placed eccentrically around said shaft and held in a fixed position by an attachment to the frame, and provided with a longitudinal 80 oil chamber open at the end by which said sleeve is held in a fixed position and communicating with an oil supply and also with one or more holes extending downwardly from the inside to the outside of the sleeve and intersecting the oil chamber, one or more eccentrics supported upon said sleeve and provided with one or more holes extending from the inside to the outside thereof, and means for bringing the holes in said eccentrics and 85 sleeve into relative positions; whereby oil may flow into them from the oil chamber and connected oil supply. 90

23. In a printing press comprising among its elements a bed and rack; a rotating shaft, two gear wheels surrounding said shaft, means for driving them in opposite directions, and further means for alternately and vertically moving each of said gear wheels in and 95 out of the path of said rack. 100

24. In a printing press comprising among its elements a bed and rack; a shaft, two gear wheels surrounding said shaft, means for rotating them in opposite directions, two eccentrics surrounding said shaft and supporting 110 said gear wheels, and means, competent to move said eccentrics through an arc of one hundred and eighty degrees, for alternately moving each of said gear wheels in and out of the path of said rack. 115

25. In a printing press comprising among its elements a bed and a single rack; means for moving the bed to and fro including a shaft supported in two bearings, a cam supported upon said shaft, two hangers suitably secured to the bed and having each a stud and roller, and means for rotating said cam to alternately engage with and disengage from said studs and rollers, to reverse the direction of the movement of the bed. 120

26. In a printing press comprising among its elements a bed and rack; a rotating shaft, two gear wheels surrounding said shaft, a sleeve supported eccentrically relatively to 125 said shaft and held in a fixed position by suit- 130

- able means, two eccentrics supported upon said sleeve and supporting said gear wheels, a gear wheel secured to one of said eccentrics concentrically to its bore, and means for oscillating said gear wheels and eccentrics upon the concentric center of said sleeve, to alternately move each of said gear wheels in and out of the path of said rack.
27. In a printing press comprising among its elements a bed and rack; a rotating shaft, two gear wheels surrounding said shaft, means for driving said gear wheels in opposite directions, means for alternately and vertically moving each of said gear wheels in and out of the path of said rack, and further means, including a body rigidly secured to said shaft, for reversing the direction of the movement of the bed.
28. In a printing press comprising among its elements a bed and rack; a rotating shaft, two gear wheels surrounding said shaft, means for driving said gear wheels in opposite directions, means for alternately moving each of said gear wheels in and out of the path of said rack, a cam rigidly secured upon said shaft, and two hangers, each provided with a stud and roller, secured to the bed, for reversing the direction of the movement of the latter.
29. In a printing press comprising among its elements a bed and rack; a cylinder, a gear wheel attached thereto, a rotating shaft, a gear wheel rigidly fixed thereon engaging with the gear wheel attached to the cylinder, means, including a second gear wheel supported around said rotating shaft, for moving the bed in one direction, a second means for moving the bed in the opposite direction, and a third means, including a body rigidly fixed upon said rotating shaft and operatively connected to said second gear wheel, for reversing the direction of the movement of the bed.
30. In a printing press comprising among its elements a bed and rack; a cylinder, a gear wheel attached thereto, a rotating shaft, a gear wheel provided with two series of teeth of the same diameter and pitch secured to each other and adjustable relatively to each other along their pitch lines, said gear wheel being rigidly secured upon the rotating shaft and directly connected to the gear wheel attached to the cylinder, and means, actuated from said shaft, for moving the bed in one direction.
31. In a printing press comprising among its elements a bed and rack; a cylinder, a gear wheel attached thereto provided with two series of teeth of the same diameter and pitch secured to each other, means for adjusting them relatively to each other along their pitch lines, a rotating shaft, a gear wheel rigidly secured thereon engaging with the gear wheel attached to the cylinder, a second gear wheel supported around said shaft, a body firmly secured upon said shaft,

an operative connection between said body and second gear wheel, to communicate motion from the former to the latter, and means for moving said second gear wheel in and out of the path of said rack.

32. In a printing press comprising among its elements a bed and rack; a cylinder, a gear wheel attached thereto, a rotating shaft, a gear wheel rigidly secured thereto engaging with the gear wheel attached to the cylinder, a second gear wheel independently supported around said shaft, a body firmly secured upon said shaft, an operative connection between said second gear wheel and body, whereby the motion of the latter is communicated to the former, and means for vertically moving said second gear wheel in and out of the path of said rack.

33. In a printing press comprising among its elements a bed and rack; a rotating shaft, two eccentrics surrounding said shaft, two gears mounted on the eccentrics, one of them being driven from the rotating shaft, and means for alternately reversing the position of said eccentrics.

34. In a printing press comprising among its elements a bed and rack; a driving pinion, a cylinder, a gear wheel attached thereto, a rotating shaft, a gear wheel rigidly secured thereon engaging directly with the gear wheel attached to the cylinder and with the driving pinion, means including said rotating shaft and gear wheel rigidly secured thereon, connected positively with the driving pinion, for moving the bed in one direction, a second means, connected positively with the driving pinion and independently of the first means, for moving the bed in the opposite direction, and a third means for reversing its direction of movement.

35. In a printing press comprising among its elements a bed and rack; a driving pinion, a cylinder, a gear wheel attached thereto, a rotating shaft, a gear wheel rigidly secured thereon engaging directly with the gear wheel attached to the cylinder and with the driving pinion, means including said rotating shaft and gear wheel rigidly secured thereon, connected positively with the driving pinion, for moving the bed in one direction, a second means, connected positively with the driving pinion and independently of the first means, for moving the bed in the opposite direction, a third means for reversing its direction of movement, and an operative connection between said second and third means.

36. In a printing press comprising among its elements a bed and rack; a cylinder, a gear wheel attached thereto, a rotating shaft supported in two bearings, a gear wheel rigidly secured thereon engaging with the gear wheel attached to the cylinder, two gear wheels supported around said shaft between the two bearings, means for rotating said

- gear wheels in opposite directions, means for alternately moving each of said gear wheels in and out of the path of said rack, and further means for reversing the direction of the movement of the bed.
37. In a printing press comprising among its elements a bed and rack; a cylinder, a gear wheel secured thereto, a rotating shaft, a gear wheel secured thereon engaging directly with the gear wheel attached to the cylinder, a second gear wheel independently supported around said shaft, and means including a movable element for communicating the motion of said shaft to said second gear wheel.
38. In a printing press comprising among its elements a bed and rack; a cylinder, a gear wheel attached thereto, a rotating shaft supported in two bearings, a gear wheel rigidly secured thereon engaging with the gear wheel attached to the cylinder, two gear wheel supported around said shaft between the bearings, means for rotating said gear wheels in opposite directions, means for alternately moving each of said gear wheels in and out of the path of said rack, two hangers suitably attached to the bed and bearing each a stud and roller, and a cam rigidly secured to said shaft between the two bearings, to alternately engage with and disengage from the said studs and rollers, to reverse the direction of the movement of the bed.
39. In a printing press comprising among its elements a bed and rack with downwardly projecting teeth; a rotating shaft supported in two bearings, a sleeve placed eccentrically relatively to said shaft and held in a fixed position by an attachment to the frame, two eccentrics supported upon said sleeve, two gear wheels supported upon said eccentrics, a gear wheel secured to a collar extended from one of the eccentrics, a geared sector engaging with the gear wheel secured to one end of a shaft having a bearing in the frame, an arm secured upon said shaft at its other end bearing a stud and roller extending into the path of a rotating cam, means for imparting a rotating motion to one of said gear wheels in a direction opposite to that of said shaft, a cam rigidly fixed upon said shaft, a stud and block secured to the other of said gear wheels engaging with a slot formed in the body of said cam, and two hangers suitably attached to the bed and bearing each a stud and roller, whereby the bed and rack are driven to and fro and reversed at each end of the to and fro movement.
40. In a printing press comprising among its elements a bed and rack, a cylinder, a gear wheel attached thereto, a main gear wheel engaged with the latter, a driving pinion engaging directly with the main gear wheel, means, including the main gear wheel and driving pinion, for moving the bed in one direction, a second means, including a rotating shaft having rigidly secured thereon a gear wheel engaging directly with the driving pinion, for moving the bed in the opposite direction, and a third means for reversing the direction of the movement of the bed.
41. In a printing press comprising among its elements a bed and rack; a driving pinion, means, connected positively therewith, for moving the bed in one direction, a second means for moving the bed in the opposite direction including among its members a rotating shaft having rigidly secured thereon a gear wheel engaging directly with the driving pinion, a third means for reversing the direction of the movement of the bed, and an operative connection between the second and third means.
42. In a printing press comprising among its elements a bed and rack with downwardly projecting teeth; a cylinder, a gear wheel attached thereto, a main gear wheel engaged with the latter, a driving pinion engaging directly with the main gear wheel, means, including the main gear wheel and driving pinion, for moving the bed in one direction, a second means, including a rotating shaft having rigidly secured thereon a gear wheel engaging directly with the driving pinion, for moving the bed in the opposite direction, and a third means for reversing the direction of the movement of the bed.
43. In a printing press comprising among its elements a bed and rack with downwardly projecting teeth; a driving pinion, means, connected positively therewith, for moving the bed in one direction, a second means, including a rotating shaft having rigidly secured thereon a gear wheel engaging directly with the driving pinion, for moving the bed in the opposite direction, a third means for reversing the direction of the movement of the bed, and an operative connection between the second and third means.
44. In a printing press comprising among its elements a bed and rack; a shaft, two gear wheels supported around the shaft independently thereof, means for rotating the gear wheels in opposite directions, and means for alternately and vertically moving each of the gear wheels in and out of the path of the rack.
45. In a printing press comprising among its elements a bed and rack; a shaft, two gear wheels supported around the shaft independently thereof, means for rotating the gear wheels in opposite directions, means for alternately and vertically moving each of the gear wheels in and out of the path of the rack, and further means for reversing the direction of the movement of the bed.
46. In a printing press comprising among its elements a bed and rack; a shaft, two gear wheels supported around the shaft independently thereof, means for rotating the

gear wheels in opposite directions including a rotating shaft having a gear wheel rigidly secured thereon engaging with one of said gear wheels, and means for alternately moving each of said gear wheels in and out of the path of the rack.

47. In a printing press comprising among its elements a bed and rack; two gear wheels supported around the shaft independently thereof, means for rotating the gear wheels in

opposite directions, two eccentrics supported around the shaft independently thereof and supporting the gear wheels, and means for alternately reversing the positions of the eccentrics and gear wheels.
